(57) **CLAIM**

The ornamental design for a wire cable tray, substantially as shown and described.

DESCRIPTION

FIG. 1 is a front perspective view of a wire cable tray of the present invention;

FIG. 2 is an end elevation view thereof;

FIG. 3 is a top plan view thereof;

FIG. 4 is a left elevation view thereof;

FIG. 5 is a bottom view thereof; and,

FIG. 6 is a sectional view thereof taken along lines 6-6 indicated in FIG. 3.

The wire cable tray has been shown broken to indicate indeterminate length.
